UNITED STATES PATENT OFFICE

172,937

TAPE DISPENSER OR SIMILAR ARTICLE

Jean O. Reinecke, Oak Park, Ill., assignor to Derby Sealers, Incorporated, Ansonia, Conn., a corporation of Connecticut

Application January 6, 1954, Serial No. 28,395

Term of patent 14 years

(Cl. D74—1)

To all whom it may concern:

Be it known that I, Jean O. Reinecke, a citizen of the United States, residing in Oak Park, in the county of Cook and State of Illinois, have invented a new, original, and ornamental Design for a Tape Dispenser or Similar Article, of which the following is a specification, reference being had to the accompanying drawings, forming part thereof in which,

Fig. 1 is a side elevational view of a tape dispenser showing my new design;

Fig. 2 is a front elevational view thereof;

Fig. 3 is a rear elevational view;

Fig. 4 is a top plan view; and

Fig. 5 is a side elevational view showing the side opposite that shown in Fig. 1.

I claim:

The ornamental design for a tape dispenser or similar article, substantially as shown.
